James F. Drummond, of New York, N.Y.

Letters Patent No. 1882-Dated Jan 5th 1864.

Design for a Bas-relief of Genl. G. B. McClellan.

The shield referred to in their Letters Patent and making part of the same.

To all whom it may concern:

Be it known that I, James F. Drummond, of the City, County, and State of New York, have invented a new Design for an Equestrian Bas-relief of Major General George B. McClellan; and I do hereby declare that the following is a full, clear, and exact description of the same, reference being had to the accompanying photograph.

The bas-relief exhibits the right side of the Figure.

The General is represented seated in upright attitude looking forward, with the reins in the left hand, the head uncovered and cap in the right hand which hangs down in an easy position. His dress consists of undress regulation coat, belt, gauntlets and high riding boots worn outside of the pantaloons.

The horse is represented as paddled, furnished with holsters and with ornamented stirrup. The position is that of having been just pulled up and stopped on a walking pace, resting on the right fore foot and left hind foot and the neck arched. The left fore foot is represented as raised to its highest position, and the right hind foot as just about to be raised from the ground.

What I claim as my invention, and desire to secure by Letters Patent, is

The design of the Equestrian Bas-relief herein described and represented in the accompanying drawings.
